United States Patent Office

Des. 230,815
Patented Mar. 19, 1974

230,815

WRENCH

Koumei Ono, 19-33-315, 5-chome, Narimasu,
Tokyo, Japan

Filed Sept. 15, 1972, Ser. No. 289,441

Claims priority, application Japan Apr. 13, 1972

Term of patent 14 years

Int. Cl. D8—05

U.S. Cl. D8—22

FIG. 2

FIG. 1

FIG. 3

FIG.4

FIG.6

FIG.5

FIG. 7

FIG. 8

FIG. 1 is a top plan view of the wrench of the present invention;

FIG. 2 is a front plan view of the said wrench;

FIG. 3 is a right side plan view of the said wrench;

FIG. 4 is a left side plan view of the said wrench;

FIG. 5 is a bottom view of the said wrench;

FIG. 6 is a front plan view of the said wrench which has been adjusted to a smaller diameter;

FIG. 7 is a cross-sectional view taken along line 7—7 of FIG. 3; and

FIG. 8 is a perspective view of the said wrench.

I claim:

The ornamental design for a wrench, as shown and described.
